JOSEPH BIJUR, OF NEW YORK, N. Y., ASSIGNOR TO THE SAFETY CAR HEATING AND LIGHTING CO., OF NEW YORK, N. Y., A CORPORATION OF NEW JERSEY.

SYSTEM OF DISTRIBUTION.

1,262,915.

Specification of Letters Patent. Patented Apr. 16, 1918.

Application filed December 21, 1910. Serial No. 598,530.

To all whom it may concern:

Be it known that I, JOSEPH BIJUR, a citizen of the United States, residing at New York, in the county of New York and State 5 of New York, have invented certain new and useful Improvements in Systems of Distribution, of which the following is a full, clear, and exact description, such as will enable others skilled in the art to which 10 it appertains to make and use the same.

This invention relates to electrical regulating apparatus. One of the objects thereof is to provide a practical and efficient system for the electric lighting of railway vehicles, in which a battery is charged from a generator driven at varying speeds. Another object is to provide sensitive and reliable apparatus of the above type in which the battery is charged at a proper rate and 15 the generator protected against over-load. Another object is to provide apparatus of the above type of simple and cheap construction and economical action. Another object is to provide a regulating device of 20 simple construction and adapted to be maintained in proper condition by unskilled labor. Other objects will be in part obvious and in part pointed out hereinafter.

The invention accordingly consists in the 25 features of construction, combinations of elements and arrangement of parts which will be exemplified in the construction hereinafter set forth, and the scope of the application of which will be indicated in the following claims.

In the accompany drawing, wherein is shown one or more of various possible embodiments of the several features of this invention,

40 Figure 1 is a diagrammatic view of a system; Fig. 2 is a plan of a regulating device;

Fig. 3 is an end view of the same;

Fig. 4 is a sectional view along the line 45 X-X of Fig. 3; and

Fig. 5 is a side elevation of a different form of regulating device.

Similar reference characters refer to similar parts throughout the several views.

50 Referring now to Fig. 1 of the drawing, there is shown at 1 a generator having the shunt field, winding 2, serially connected with which is a variable resistance medium 3, which is here shown as comprising a pair 55 of sets of contacting members, as carbon

disks, through which the current passes in series. The construction of this device will hereinafter be given in detail, but it may here be noted that it is adapted upon being compressed to decrease the aggregate resistance of the field circuit and increase the generator output, a decrease of pressure, obviously, having the opposite effect. A storage or secondary battery 4 is connected with the generator through the main 5, in which is 60 serially disposed the main switch 6 of a well-known construction. The remaining connection of the battery, by conductor 7, leads through a current coil 8 and thence to the main 9 which leads to the generator terminal. The latter main leads past the battery to the lamps 10, the term "lamps" being used in a broad sense to denote any form of translating devices. Conductor 5 is also extended past the battery branch and 70 leads through a current coil 11 and a variable resistance device 12 to the lamps. The latter resistance is controlled by a voltage coil 13 connected across the lamps, as indicated in the drawing.

80 In a circuit across the battery 4 is a voltage coil 14, and it may here be noted that all voltage coils are provided with a serially disposed resistance element of zero temperature co-efficient, in order to reduce the effect 85 of temperature variation upon the coils and render their action more accurate. It may also be noted that the expression "connected in a circuit across the battery," with reference to the coil 14, is intended to imply that the potential drop in this circuit is substantially equal to the voltage across the mains and not necessarily exactly that across the battery terminals.

Coacting with the several coils 8, 11 and 95 14 and adapted to be conjointly acted upon thereby is a swinging arm 15, pivoted as at 16 and provided with a projection 17, which is connected with the link 18 of the variable resistance device. Accordingly, as the arm 100 15 is swung downwardly or in a counter-clockwise direction, the pressure plate 19 is moved away from the resistance medium 3 and the resistance of the field circuit of the generator correspondingly increased.

105 Referring now to Fig. 2 of the drawing, in which the variable resistance device appears in detail, there is shown a frame 20, to which are adjustably secured the two fixed plates 21. Upon this frame, between 110

each fixed plate 21 and the movable pressure plate 19, is mounted a set of carbon disks, the two sets in series comprising the resistance medium 3, these disks being held 5 in position as by the rods 22 with suitable insulating sleeves. Operatively related to the movable pressure plate 19 is an electromagnet 23, so disposed as to tend to attract plate 19 and compress the medium 3. This 10 electromagnet is preferably connected across the mains as a voltage coil and is so wound and proportioned and its armature so shaped that its pull upon the pressure plate 19 is at all stages of compression of the medium substantially 15 equal to the mechanical resistance of this medium to compression. In other words, the mechanical resistance to compression increases at an increasing rate as compression progresses and the attraction 20 of this magnet 23 for its armature increases at substantially the same rate, and the parts are so proportioned that at all stages of operation of the device the compressive force exerted by magnet 23 is substantially equal 25 to the resistance to compression of the medium 3. The device is thus continually in a state in which these two forces are substantially balanced and any change in the force applied to the medium by the regulating magnets will exert its full effect in 30 changing the electrical resistance of the medium irrespective of the state of mechanical compression in which the resistance happens to be. In other words, the mechanical resistance 35 of the carbons to compression being just balanced at all stages of compression by the coil 23, the only resistance varying forces are the spring 25 and the magnetic attraction upon the lever 15, and hence on 40 actuation of the lever it will move until the force of the spring is just balanced. This entire device, including the frame 20, is detachable as a unit from the frame 24, which may support the actuating lever 15 and the 45 adjustable retractile spring 25. From this it will be seen that this unitary device may be removed and replaced as a unit without the necessity for adjustment by skilled labor, as it is so formed and proportioned as properly 50 to perform its functions when connected in position.

In Fig. 5 of the drawing is shown a resistance device in which certain of the features of this invention are embodied. The frame 26 may be removably mounted upon the frame 24 and the link 18 connected with the lever arm 17. The variable resistance medium 28 is compressed between a fixed plate 29 and a movable plate 30 and lever 27 60 on link 18 is connected with the frame 26 by a toggle comprising the jointed levers 31 and 32, this toggle acting on the pressure plate 30 through link 18. Lever 32 is provided with a weight 33 and a stop 34 for this lever is so disposed that it will limit

the downward movement of the linkage. These parts are so formed and proportioned that the pressure exerted by weight 33 upon the medium 28 is substantially equal to the resistance of this medium to compression at 70 all stages, and, accordingly, the device is at all times sensitive to a slight impulse in either direction from the actuating mechanism. This follows in view of the action previously explained with respect to the 75 apparatus of Fig. 2, the rapidly increasing compressive power of the toggle in this case taking the place of the rapidly increasing attractive power of the magnet 23. In other words, as the weight 33 falls the above toggle approaches a position in which the several pivotal points are in line and hence exerts a pull upon the lever 27, which increases at a rapidly increasing rate as it nears this position. This rate of increasing 80 pressure by a suitable proportioning of the parts may be made to follow closely the increasing resistance to compression as the compression progresses.

Recurring to Fig. 1 of the drawing, there 85 is shown a voltage coil 35 connected across the battery and the armature 36 of this coil controls the position of contacts 37 and 38. Contact 37 short-circuits the coil 11 and contact 38 short-circuits the resistance element 39, serially connected with the voltage coil 14.

The operation of the above-described apparatus is substantially as follows:—

Assuming the generator to be speeded up 100 until the main switch 6 closes, the battery will receive charging current, which is governed by the coils 8 and 14. These coils are so wound and proportioned that with the full desired battery charging current for empty 105 battery in coil 8 and the corresponding voltage in coil 14, they will just balance the retractile force of spring 25. If there is any tendency of excess of either of these factors, the resistance medium 3 will be relieved 110 of pressure and conditions again brought to normal. These coils, moreover, are so formed that with the desired current flowing in coil 8 for a fully charged battery and the corresponding voltage in coil 14, they 115 will also just balance the opposing forces of the variable resistance mechanism. The above is under the assumption, of course, that there is no lamp-load turned on. If the lamp-load be turned on, the current will flow 120 through coil 11 and this coil is so wound and proportioned that with a lamp-load equal to the full capacity of the generator and a voltage across coil 14 equal to the discharging voltage of a full battery, these two coils will 125 just balance the resistance device with zero current in coil 8. The action of the cut-off device is such that upon the battery reaching a stage where it is desired to stop the charging current, the coil 11 will be short-circuited 130

and coil 14 so increased in value, due to short-circuiting of resistance element 39, that it will just balance the regulating device with zero current in coil 8.

- 5 In order to render clearer the action of this regulating apparatus, certain concrete examples will be given. Assume that the railway car is equipped with a generator having a normal capacity of 65 amperes capable of carrying over-loads of 72 amperes and that 16 cells of storage batteries are used which, when the voltage across their terminals exceeds $2\frac{7}{16}$ volts per cell, will take a charging current, and which, when the 10 voltage across their terminals is below this value, will discharge. Thus $2\frac{7}{16}$ volts per cell is assumed as a point to which the voltage across the terminals of the storage battery may be reduced before discharge begins.
- 15 20 Since either the coil 23 or the toggle arrangement shown in Fig. 5 are intended to compensate for the increasing resistance to compression of the carbon pile, the changes in the resistance in the carbon pile will be proportional to the variation in pull on the 25 spring 25 caused by the current in the coils of the regulator.

The batteries are assumed to be full when the voltage across their terminals has risen 30 to $2\frac{7}{16}$ volts per cell at the same time that the charging current has fallen to $18\frac{1}{2}$ amperes.

When the volts across coil 14 are $2\frac{7}{16}$ volts per cell and the current in coil 8 is $18\frac{1}{2}$ amperes, the sum of the pulls is made equal to the mechanical pull of the regulator in the opposite direction. The sum of these pulls, therefore, is the value which causes the regulator to be in balance. Any excess rotates 40 it counterclockwise; any decrease in the pull rotates it clockwise. The proportions between coils 14 and 8 are made to fit these two conditions; $2\frac{7}{16}$ volts across coil 14, the voltage corresponding to a full battery, and 45 $18\frac{1}{2}$ amperes in coil 8, the desired finishing charge for a full battery, produce a certain pull and $2\frac{7}{16}$ volts per cell across coil 14, the voltage corresponding to an empty battery at the beginning of the charge, and 65 amperes in coil 8, the full value of charge 50 available for an empty battery, produce the same pull. This fixes the proportions of 14 and 8. The proportions of coil 11 with relation to the other two may be fixed as follows: 72 amperes in coil 11, the lamp consumption of about the over-load capacity of the generator, with $2\frac{7}{16}$ volts per cell across 55 14, the voltage at which the battery is about to discharge, zero current in 8, zero battery charge since the whole generator output is required by the lamps, equals the same counter-clockwise pull on the lever arm 15 of the regulator.

From the above proportions, it will be 60 seen that without any lamp load the battery

current coil and the battery voltage coil alone cause a suitable battery charge to take place, the current being about the full generator output if the battery is empty and reduced to a suitable value when the battery is full. The effect of the current flowing to the lamps is such that if it should rise to the full capacity of the generator, the balance of the regulator is produced with no charge into the battery and the generator voltage reduced to such a point that further lamp load will cause the battery to discharge and so furnish the current assumed to be in excess of the generator capacity. A full load to the translating devices causes the 70 generator potential to be lowered to the point at which the battery discharges. The generator is, therefore, protected against over-load due to the translating devices or an empty battery or both. Similarly, full 75 generator output to the battery causes the voltage of the generator to be so reduced that the battery charge will not rise above this value. A slight decrease in the lamp load, so that it lies within the capacity of 80 the generator, permits current to flow to the battery, if it is not yet full, and this regulator has marked advantages in this respect, since even with a relatively large proportion of the generator output used by the 85 translating devices, almost all of the remaining generator capacity is available for 90 charging the battery.

Among other advantages of this regulator are its simplicity in that while having 100 few parts, the generator is so controlled that the battery charge proceeds in accordance with the battery requirements, substantially irrespective of lamp load, so long as the total current output is within the capacity of 105 the generator. All current required by the translating devices is furnished by the generator, if the latter is up to speed, and the battery furnishes current to them only at such times as the generator is incapable of 110 doing so by reason of slow speed.

In the action of the battery cut-off under the above assumption, the value of the resistance 39 is such that when short-circuited, coil 14 produces the above constant pull with $2\frac{7}{16}$ volts across its terminals and no current in coil 8. When the battery reaches a predetermined condition of charge, the battery cut-off closes and short-circuits the resistance, whereupon the generator is 115 regulated at the floating point of the battery, $2\frac{7}{16}$ volts per cell with no current flowing to the battery. The battery cut-off also short-circuits coil 11 so that the generator is maintained at the floating point of the 120 battery, irrespective of the lamp load. This condition persists until the main switch 6 opens when the cut-off opens and the charge 125 proceeds in the manner first described.

In the action of the variable resistance 130

device, it is desirable to have the dynamo regulator follow the same law of operation, irrespective of its position in its range. If the carbons by reason of their compression 5 oppose the motion of the regulator, the same force that balances the regulator when the carbons are open and exert no turning influence will be different from the force which balances the regulator when the carbons 10 are compressed and tend to turn the regulator. By the above means a unitary variable resistance device can be constructed in which the expanding force of the carbons themselves is offset and compensated 15 for by the opposite pull of the compensating means. If the carbons exert no expanding force when open and exert a five pound resistance to compression when 20 squeezed, the parts of the toggle or the magnet are so proportioned that it pulls five pounds more in a horizontal direction when the carbons are squeezed than when they are open, and may be made to compensate very closely all expanding forces of the carbons 25 between the limits of open and squeezed.

It will thus be seen that there is provided apparatus in which the several objects of this invention are attained.

As many changes could be made in the 30 above construction and many apparently widely different embodiments of this invention could be made without departing from the scope thereof, it is intended that all matter contained in the above description or 35 shown in the accompanying drawing shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent is:

1. In apparatus of the class described, in combination, a generator, a storage battery 50 and lamps connected to receive current from said generator, a pressure-controlled variable resistance for affecting the output of the generator, a voltage responsive coil acting upon said resistance, a battery current 55 coil acting upon said resistance, each of said coils constantly exerting a substantial regulating effect upon said resistance, and means varying with the charge of said storage battery to cause said voltage coil to exert a preponderating effect over said current coil when said battery substantially reaches a state of full charge.

2. In apparatus of the class described, in combination, a generator having a shunt 60 field, a storage battery and translation cir-

cuit connected to receive current from said generator, a pressure-controlled variable resistance in the shunt field circuit of said generator, a voltage responsive coil exerting a substantially constant effect upon said resistance throughout a substantial portion of the charge of said battery, a battery current coil adapted to regulate said generator for slightly diminishing the battery charging current throughout a substantial portion of the charge of said battery, and means varying with the charge of said battery adapted to increase the effect of said voltage coil when said battery reaches a predetermined state of charge, whereby said voltage coil causes a gradual decreasing regulating effect of said current coil. 70 75 80

3. In apparatus of the class described, in combination a generator, a storage battery and lamps connected to receive current from said generator, a pressure-controlled variable resistance for affecting the output of the generator, a multiplying lever operating upon said variable resistance, a voltage responsive coil and a current responsive coil 90 acting conjointly upon one end of said lever and constantly exerting a substantial regulating effect upon said resistance, and means varying with the charge of said storage battery to cause said voltage coil to exert a 95 preponderating effect over said current coil when said battery substantially reaches a state of full charge.

4. In apparatus of the class described, in combination a generator, a storage battery 100 and lamps connected to receive current from said generator, a pressure-controlled variable resistance for affecting the output of the generator, a non-polarized multiplying lever operating upon said variable resistance, a voltage responsive coil and a current responsive coil acting conjointly upon one end of said lever and constantly exerting a substantial regulating effect upon said 105 resistance, and means varying with the charge of said storage battery to cause said voltage coil to exert a preponderating effect over said current coil when said battery substantially reaches a state of full charge. 110

5. In apparatus of the character described, in combination, a generator, a storage battery and lamps adapted to receive current from the generator, a variable resistance device connected to affect the output of said generator, means comprising a 115 coil carrying the current passing to said lamps adapted to affect said variable resistance device, and means to shunt said lamp current coil when said battery reaches a predetermined condition of charge. 120 125

6. In apparatus of the character described, in combination, a generator, a storage battery and lamps connected to receive current from the generator, a variable resistance device connected to affect the output 130

of the generator, means comprising a voltage coil connected in a circuit across said battery, a coil connected to be traversed by current passing to said lamps and adapted by 5 to affect said device conjointly with said voltage coil, and means to give an increased effect to said voltage coil and decreased effect to said lamp current coil when said battery reaches a predetermined condition of 10 charge.

7. In apparatus of the class described, in combination, a generator, a storage battery, a variable resistance medium positioned and connected to affect the output of said generator, a current coil connected to receive the current passing to said battery and wound to exert a field substantially proportional thereto, a circuit connected across said battery, a voltage coil in said circuit 20 and forming a magnet independent of said current coil, means controlled by said coils and controlling said variable resistance medium, and means controlled in accordance with the voltage of said battery adapted 25 upon said battery reaching a predetermined voltage to give an increased effect to said voltage coil.

8. In apparatus of the class described, in combination, a generator, a storage battery 30 and lamps adapted to receive current therefrom, a variable resistance device positioned and connected to affect the output of said generator, a current coil connected in the external circuit of said generator, a second 35 current coil wound and connected to receive the current passing to said lamps and present a field substantially proportional thereto, a circuit across said battery, a voltage coil in said last named circuit, and means 40 controlled by said coils and controlling said variable resistance device, said coils being wound and mounted to exert a cumulative effect upon said last means.

9. In apparatus of the class described, in combination, a generator, a storage battery and lamps adapted to receive current therefrom, a variable resistance device positioned and connected to affect the output of said generator, a current coil connected in the external circuit of said generator, a second 50 current coil wound and connected to receive the current passing to said lamps and present a field substantially proportional thereto, a voltage coil connected in a circuit 55 across said battery, and means controlled by said coils and controlling said variable resistance device, said several coils being so wound and proportioned as conjointly to exert a cumulative effect upon said resistance device with full battery charging voltage, a predetermined finishing charging current in said first current coil and zero current in 60 said second current coil substantially equal to their effect thereon with full battery dis- 65 charging voltage, zero current in said first

current coil and the full capacity of the generator in said second current coil.

10. In apparatus of the class described, in combination, a generator, a storage battery and lamps adapted to receive current therefrom, a variable resistance device positioned and connected to affect the output of said generator, a current coil connected in the external circuit of said generator, a second current coil wound and connected to receive 70 the current passing to said lamps and present a field substantially proportional thereto, a circuit across said battery, a voltage coil in said last named circuit, and means controlled by said coils and controlling said 80 variable resistance device, said several coils being so wound and proportioned as conjointly to exert a cumulative effect on said resistance device with empty battery charging voltage, a predetermined full charging 85 current in said first current coil and zero current in said second current coil substantially equal to their effect thereon with full battery discharging voltage, zero current in said first current coil and the full capacity 90 of the generator in said second current coil.

11. In apparatus of the class described, in combination, a generator, a storage battery and lamps adapted to receive current therefrom, a pressure-controlled variable resistance device positioned and connected to affect the output of said generator, a current coil connected in the external circuit of said generator, a second current coil wound and connected to receive the current 95 passing to said lamps and present a field substantially proportional thereto, said coils being wound and mounted to exert a cumulative effect, a circuit across said battery, a voltage coil in said last named circuit, and 100 means controlled by said coils and controlling said variable resistance device.

12. In apparatus of the class described, in combination, a generator, a storage battery and lamps connected to receive current from 110 said generator, a pressure-controlled variable resistance device connected to affect the output of said generator, a current coil positioned in the battery branch to present a field substantially proportional to the current flowing to the battery, a current coil connected in the lamp branch to present a field substantially proportional to the current flowing to the lamps, a circuit across 115 said battery, a voltage coil in said circuit a 120 member adapted to be acted upon conjointly and cumulatively by said coils to vary the pressure upon said variable resistance medium, and means adapted to oppose the effect of said coils upon said medium. 125

13. In apparatus of the class described, in combination, a generator, a storage battery and lamps connected to receive current from said generator, a variable resistance device connected to affect the output of said gen- 130

erator, means comprising a coil carrying the current passing to said lamps adapted to affect said variable resistance device, and means controlled in accordance with the voltage of said battery adapted upon said battery reaching a predetermined voltage to shunt said lamp current coil.

14. In apparatus of the class described, in combination, a generator, a storage battery and lamps connected to receive current from said generator, a variable resistance device connected to affect the output of said generator, means comprising a voltage coil connected in a circuit across said battery and a coil connected in the lamp branch to carry current passing to said lamps adapted to affect said variable resistance device, and means controlled in accordance with the voltage of said battery adapted upon the battery reaching a predetermined voltage to give an increased effect to said voltage coil and decreased effect to said lamp current coil.

15. In apparatus of the class described, in combination, a generator, a storage battery, a pressure controlled variable resistance medium positioned and connected to affect the output of said generator, a current coil connected in the external circuit of said generator, a circuit across said battery, a voltage coil in said last named circuit means controlled by said coils and controlling said variable resistance medium, and means controlled in accordance with the voltage of said battery adapted upon said battery reaching a predetermined voltage to increase the effect of said voltage coil to such a de-

gree that it exerts an effect on said variable resistance medium substantially equal to the conjoint effect thereon of said voltage coil with empty battery charging voltage and said current coil with a predetermined full charging current.

16. In apparatus of the class described, in combination, a generator, a storage battery and lamps adapted to receive current therefrom, a variable resistance device positioned and connected to affect the output of said generator, a current coil connected in the external circuit of said generator, a second current coil wound and connected to receive the current passing to said lamps and present a field substantially proportional thereto, a circuit across said battery, a voltage coil in said last named circuit means controlled by said coils and controlling said variable resistance device, and means controlled in accordance with battery voltage adapted upon the battery reaching full voltage to shunt said lamp current coil and increase the effect of said voltage coil to such a degree that it exerts an effect upon said variable resistance device substantially equal to the conjoint effect thereon of said voltage coil with empty battery charging voltage and said first coil with a predetermined full charging current.

In testimony whereof I affix my signature, in the presence of two witnesses.

JOSEPH BIJUR.
